UNITED STATES PATENT OFFICE.

ORRIN H. BURDICK, OF AUBURN, NEW YORK, ASSIGNOR TO HIMSELF AND
DAVID M. OSBORNE.

IMPROVEMENT IN FASTENINGS FOR FLASKS OR MOLDS.

Specification forming part of Letters Patent No. 42,543, dated April 26, 1864.

To all whom it may concern.

Be it known that I, ORRIN H. BURDICK, of Auburn, in the county of Cayuga and State of New York, have invented certain new and useful Improvements in Fastenings for Flasks, Molds, &c., for Casting Metals in; and I do hereby declare that the following is a full, clear, and exact description of the same, reference being had to the accompanying drawings, making a part of this specification, in which—

Figure 1 represents an elevation of a flask set up and fastened and ready to receive the pouring of the metal. Fig. 2 represents a front view of one of the fastenings of full size. Fig. 3 represents a horizontal and Fig. 4 a vertical section through the same, as represented in Fig. 2.

Similar letters of reference, wherever they occur in the separate figures, denote like parts in all the drawings.

Flasks or molds are always composed of at least two parts—viz., the nowel and the cope—and sometimes of more than two parts, without including the base. The nowel contains the bulk of the casting, and consequently is subjected to the greatest degree of heat, which draws its sides together, or toward the heat, and on this account any kind of fastenings of a permanent character and which serve as guides and at the same time make a close and secure connection will fail, because the nowel will shrink or be drawn away by the heat and will take its part of the fastening with it. One part of my invention aims at remedying this defect by making one part of the fastening adjustable, so that as it is drawn out of its exact position it may be returned again almost instantly and without jarring or damage to the mold.

Another difficulty experienced in the use of the fastenings as now made is that in pressing the cope down and fitting it upon the nowel, as also in lifting it up and drawing it therefrom, unless the same is done with very great care and precision, some part of the tongue, pin, or hook will pinch or bind upon the hole, clasp, or eye into or through which it passes, and thereby not only greatly impede and obstruct the operation, but also frequently jar and injure the sand-mold within. The second part of my invention and improvement is intended to obviate this defect

among others; and it consists in the use of a tongue on one part of the fastening and a recess of corresponding shape upon the other, said tongue being made slightly slanting from the side of the flask, whereby all tendency to bind or pinch when the cope is being pressed upon and fitted to the nowel or when being lifted or taken therefrom is entirely obviated.

Another difficulty experienced in using the present mode of fastening arises from the fact that no contrivance heretofore known or used serves to lock the parts together simply and securely and so as to keep them in proper position both vertically and laterally, and the third part of my invention and improvement is intended to furnish a method of so fastening the parts of the flask together as to obviate these among other difficulties; and it consists in making the lower part of the shoulder, which is upon the lower part of the fastening and of considerable length, straight, so that when the key or pin is thrust through upon the outside of the flask and along said lower surface of said shoulder in its whole length and into and through the slot or notch in the tongue intended to receive it, it will not only press against the lower surface of said shoulder, but also against the surface of the lower part of said notch, and thus securely lock and hold the parts in place both laterally and vertically.

To enable others skilled in the art to make and use my invention, I will proceed to describe the same with reference to the drawings.

In Fig. 1, A represents the cope, B the nowel, and C the base, of an ordinary flask, which parts are represented as held together and matched by my fastenings at the sides and ends, and by one, two, or more sets of fastenings, as may be required. The fastening is made of two parts D E, of which the part D may be flat and fastened to the cope or the base or bottom board, as the case may be, while the other part E is made convex on its back and is fastened to the mold. The cope and base-board can be braced, so as not to be drawn out of a true line by the heat of the casting; but the nowel cannot be braced, and consequently will be drawn inward by the heat, and for this reason the part E, which is the compensating part or portion, is united to

the nowel. On the part E of the fastening there is a recess *a a*, which I make angular; but the particular form whereof is not material, and on the part D there is a tongue *c c* of corresponding form to fit the recess, and when the two are slid together they gage and match the two parts of the flask, to which they are respectively attached both vertically and laterally, and bring them together with great precision and without any jar. The under surface of the two parts forming the recess *a a* is made straight, so as to constitute a shoulder, against which the key or pin *n* presses when the parts are locked together. Upon the inner side of the tongue a notch or slot is made, the upper part whereof is flush with or above the lower surface of the shoulder, and when the two parts of the fastening come together there is an opening *i* through between the outer surface of the under part of the fastening and in the notch so made in the tongue of the other part of said fastening, so that an ordinary nail *n*, passed through said opening horizontally, locks them both tightly and securely together, both vertically and laterally. The recess *a a* being open and not like dowel pins and holes and the tongue being slanted slightly from the sides of the flask, they guide and match readily and may be fitted together without the least jar or trouble. The convex part E, as shown more particu-

larly in Fig. 4, stands off from the nowel, and by means of the set-screw *m*, passing through this portion and into the nowel and the permanent screws *o o*, the nowel may be drawn out, so as to match the tongue of the other portion whenever it warps or is drawn in by the heat.

To fasten the key to the flasks causes much trouble, as it is constantly getting in the way. When loose, it is often mislaid or lost. For these reasons I prefer using a common nail, which can always be conveniently had.

Having thus fully described my invention, what I claim is—

1. Making the part E of a two-part fastening for flasks convex, substantially as and for the purpose described.
2. In combination with the two parts E and D, the recess in the one and the corresponding tongue in the other, substantially as and for the purpose described.
3. The combination of the tongue, the corresponding recess, and the key or pin for locking and holding together the different parts of a flask, substantially as and for the purposes described.

O. H. BURDICK.
